UNITED STATES PATENT OFFICE

GEORGE M. BICKNELL, OF ST. LOUIS, MISSOURI, ASSIGNOR TO CARTER CARBURETOR CORPORATION, OF ST. LOUIS, MISSOURI, A CORPORATION OF DELAWARE

CARBURETOR

Application filed June 28, 1930. Serial No. 464,451.

It will be understood that the invention is susceptible of many modifications, and, accordingly, I do not wish to be limited in my protection, except as set forth in the accompanying claims.

This invention relates to carburetors, and particularly to carburetors of the type in which the spray of fuel and air is discharged from the nozzle in a downward direction.

10 It is an object of the invention to produce a carburetor of this general type in which the air passages may be made as large and unrestricted as possible in order to permit the motor to draw in the fullest possible charges, and thereby attain the maximum volumetric efficiency; it is a further object of this invention to produce a suction operated spray carburetor having one or more suction operated nozzles for supplying the full requirements of fuel to the carburetor during constant speed operation, and an accelerating device for supplying additional fuel for acceleration purposes, said accelerating device being entirely independent of the suction which may exist in said carburetor.

15 It is a further object of this invention to provide a suction operated spray carburetor of down draft type, having suction operated fuel supply devices for constant speed operation, and an accelerating device for acceleration only, with means for directing the fuel from said accelerating device to a point of maximum suction in said carburetor, without permitting the fuel to come in contact with the outer wall of the mixing conduit and to thereby avoid the difficulties in distribution which might arise during low speed operation if the fuel from the accelerating pump should be permitted to come in contact 20 with and trickle down one side of the mixing conduit.

25 It is a further object of this invention to produce a generally new and improved structure of the above described character.

30 The invention will be better understood upon reference to the following description and claims and the accompanying drawings, referring to which:

35 Figure 1 shows a diagrammatic vertical sectional view of the carburetor taken along 14, as shown in Figure 3, or other suitable

the broken line 1—1 of Figure 3 and looking in the direction of the arrows, certain parts being broken away for better illustration of others.

Figure 2 shows a vertical sectional view of 55 the carburetor taken along the line 2—2 of Figure 3 looking in the direction of the arrows, the choke being shown in closed position.

Figure 3 shows a plan view of the carburetor.

Figure 4 shows a sectional plan view of parts of the carburetor taken along the line 4—4 of Figure 2.

Figure 5 is a detailed view showing the upwardly conducting idle tube.

Figure 6 is a detailed view showing the downwardly conducting idle tube.

Figure 7 shows a sectional view of the pump discharge jet and associated parts taken along 70 the line 3—3 of Figure 3 looking in the direction of the arrows.

Figure 8 is a detail sectional view of the thimble 23.

The carburetor comprises a main body 75 member 1, having a vertically extending air chamber 2 at the upper end thereof. This passageway is contracted into a venturi, the throat of which is indicated at 3, and the venturi tapers gradually downwardly and 80 outwardly as indicated at 4, terminating in the cylindrical outlet passageway 5. This outlet is surrounded by a flange 6 which is provided with bolt holes 7 or any suitable means by which it may be attached to the 85 manifold on an internal combustion engine.

A butterfly throttle 8 mounted in conventional manner upon a shaft 9 is provided, and an operating arm 10 is attached to the shaft 9 for operation by any suitable means. The upper part of the body of the carburetor is expanded to a size sufficient to receive the fuel bowl 11 which is attached to a support member 12. The upper rim of the bowl is held in fluid tight relation to the support 95 member at 13, a suitable gasket being provided as shown. The support member is carried on the upper end of the body of the carburetor and retained in position by bolts 100

means. The support member is provided with an extension 15 extending downwardly into the bowl 11 and this extension is threaded at 16 to receive the end of a flanged nozzle member or inverted stand-pipe 17 which when screwed into the threads 16 retains the fuel bowl tightly in place. The standpipe is provided with a restricted portion or primary venturi 18 which tapers gradually out to the cylindrical bore 19 of the standpipe.

The extension 15 of the support member is provided with a well or downwardly extending opening 20 which is in communication with the atmosphere at its upper end. In the lower portion of this well a concentric member 21 is fitted and this member carries an accelerating well 22 and an inverted thimble 23 having one or more accelerating holes 24 formed therein. The member 21 is provided with a bore 25 to loosely receive a nozzle member 26. This nozzle member extends upwardly to a point just above the float level in the bowl and below the top of the thimble as shown, and it extends downwardly to a point near the throat of the venturi 18. It will be understood that the nozzle member is attached to the support member 12 by threads 27 or other suitable means.

A spider or cross member 28 is formed in the member 12 to extend across the lower part of the well 20 to receive the threads 25 and 27. A bore 29 is formed extending transversely into the extension 15 and longitudinally through the spider 28. This bore is threaded as shown to receive a jet nozzle 30 which controls the main fuel entrance to the carburetor. It will be understood that the bore 29 communicates with the bore 25 and through the accelerating holes 24 with the well 22.

Fuel is supplied to the fuel bowl 11 from a conventional fuel pump, (not shown) or other suitable means. A pipe connection 31 receives the fuel and delivers it to a passage 32 in the support member. A vertical bore 33 is formed in the support member and communicates with the interior of the fuel bowl and with the bore 32. A valve seat member 34 is threaded into the bore 33, and a needle valve 35 is mounted to seat in the member 34 to control the admission of fuel to the carburetor. A conventional float 36, pivoted at 37 operates the valve, thereby maintaining a fuel level in the carburetor substantially at the line A—A, as shown in Figure 1.

The support member 12 is provided with a vertical bore to receive the idling tube 38 as shown. This bore intersects the bore 29 to receive fuel therefrom. The tube 38 is provided with a restricted portion 39 in which is formed a small metering port 40 which initially controls the richness of the idling mixture. The second port 41 is formed in the upper end of the tube 38 to discharge into the chamber 42 at the upper end of the tube. A

plug 43 is soldered to the upper end of the tube 38 and closes the upper end of the chamber.

A transverse bore 45 communicates with the chamber 42 and also with a second chamber 46 to supply fuel to the upper end of a downwardly conducting idling conduit or tube 47. The upper end of the chamber 46 is plugged as indicated at 47, and a calibrated air bleed 44 is formed in this plug. The lower end of the tube 47 is connected to a transverse bore 48 which in turn connects with a vertical bore 49 in the body member. A port 50 somewhat longer in its vertical dimensions than the thickness of the throttle 8 provides communication between the bore 49 and the discharge outlet 51 and mixing chamber 52 of the carburetor.

A pump cylinder 53 is attached by suitable means such as cap screws 54 to the support member 12. An inlet and discharge passage 55 leads from the lower end of the pump cylinder to a point near the upper end of the cylinder where it communicates with the transverse passage 56 in the support member. The passage 56 communicates with a discharge outlet 57 through a check valve 58 and with a spray nozzle 59 as shown in Figure 7. The inlet conduit for the pump is a tube 60 threaded into the body member 12 as shown and extending below the level of the fuel in the bowl 11. An inlet check valve 61 is mounted in the tube to be held closed by its own weight except when opened by the suction of the pump. The upper end of the inlet conduit 60 communicates with a vertical bore 57 and a cross hole 62 serves to convey fuel from the bore 57 to the bore 56.

The pump is provided with a piston 63 which is connected by a link 64 and connecting rod 65 to the operating arm 10 of the throttle. A choke member 66 of frusto-conical formation is mounted on the stand-pipe 19. The choke member is provided with an annular recess 67 which is engaged by the arms of the yoke 68 mounted on a rock shaft 69. Suitable connections are made for manually operating the rock shaft so that the choke may be moved into the space between the venturi and the standpipe as shown in Figure 2 for starting purposes, and returned to the position shown in Figure 1 for normal operating conditions. The operation of the device is as follows:

Fuel being supplied to the carburetor through the connection 31 it is maintained at substantially the level A—A by the float mechanism in a conventional manner. This fuel passes through the metering jet 30 into the bore 29 and up around the nozzle 26 in the bore 25 to the same level as in the bowl. The fuel also flows out through the accelerating holes 24 in the thimble and fills up the well 22 to the same level. Fuel also flows into the idling tube 38 through the port 40.

When the engine is to be started cold the throttle is slightly opened and the choke 66 is moved into the position shown in Figure 2 thus cutting off the flow of air through the 5 annular passage between the end of the stand-pipe and the throat of the venturi. The suction of the engine as it is operated by the starting means draws the air through the stand-pipe and the primary venturi 18 which, 10 being restricted by the end of the nozzle 26, produces a high velocity in the air stream at that point. The suction communicates through the nozzle with the well 22 and fuel is drawn up to the top of the nozzle through 15 the space between the thimble 23 and the upper end to the nozzle. As soon as the engine starts to operate under its own power its speed will increase and the increased suction will lower the level of fuel in the well 22 so 20 that air will be drawn in through the accelerating holes 24 preparing the fuel in the form of an emulsion for breaking up into a spray at the throat of the primary venturi.

The increased suction will also cause fuel 25 to be drawn up through the tube 38 and the connecting passages to the port 50 where it will be discharged along with air, which is bled in at the port 44. When the engine is sufficiently warmed up the choke 66 is wholly 30 or partially withdrawn to the position shown in Figure 1 and a comparatively large quantity of air passes down through the space between the bowl of the carburetor and the enlarged portion of the body member 1 so 35 that the mixture is further diluted in the mixing chamber 52. It will be understood that the suction continues to draw fuel from the nozzle as heretofore described, but less rapidly when the choke is withdrawn than 40 otherwise.

When the throttle is substantially closed and the choke 66 is in the position shown in Figure 1 there will be substantially no suction in the mixing chamber 52 to draw fuel from the nozzle and under these conditions the requirements of the motor will be met by fuel which is drawn in through the port 50 from the idling tubes. It will be understood that the position of the edge of the throttle 45 valve 8 with respect to the port 50 will control the amount of suction applied at that port and that when the throttle valve is slightly opened the area of this port which is exposed to the suction, becomes greater, thus tending to draw in more fuel as the motor requires it.

The throttle is so connected to the accelerating pump that upon a closing movement of the throttle the pump piston will be withdrawn, drawing in a charge of fuel past the check valve 61 and through the connecting passages into the pump cylinder. Upon an opening movement of the throttle the fuel is discharged from the cylinder past the check 50 valve 58 and squirted through the nozzle 59

down into the primary inlet to prevent the tendency to undue leanness when the motor is suddenly accelerated.

It will be noted that the nozzle 59 is mounted to discharge into a substantially unrestricted portion of the primary air inlet which is anterior to the primary and main venturis, so that suction developed during high speed operation of the carburetor will not cause a continuous discharge of fuel 70 therethrough. It will also be noted that when the velocity of air flowing through the carburetor is not sufficient to instantly break up and vaporize the stream of fuel discharged from the nozzle 59, this stream will 75 come in contact with and trickle down the walls of the primary mixing conduit to the lower end of the member 19, where it will be dripped off at the throat of the venturi 3, at 80 which point the velocity of air is comparatively high. In this manner I can obtain a construction in which the accelerating pump will not be caused to discharge fuel at constant high speed operation of the carburetor and yet the fuel from the pump will be conveyed into the middle of the air stream at the main venturi so that the maximum vaporization will be obtained.

I claim:—

1. In a carburetor, a body member having 95 an annular seat, an extension of said body member substantially co-axial with said seat; a down draft passageway in said extension; a standpipe threaded into the lower end of said extension and having a flange thereon, and a 100 fuel bowl having its upper rim held in contact with said seat by screwing said standpipe in place.

2. In a carburetor a downwardly discharging fuel nozzle; a thimble fitted over the end 105 of said nozzle and forming an annular passageway between said thimble and said nozzle; means for maintaining a fuel level in said thimble at a point near the upper end of said nozzle, a well surrounding said thimble 110 and a port in the wall of said thimble at least a portion of said port being above said fuel level.

3. In a carburetor, a downwardly discharging fuel nozzle; a thimble fitted over the end 115 of said nozzle and forming an annular passageway between said thimble and said nozzle; means for maintaining a fuel level in said thimble at a point near the upper end of said nozzle, a well surrounding said thimble 120 and a plurality of vertically spaced ports in the wall of said thimble.

4. In a carburetor, a downwardly conducting passageway; a concentric fuel nozzle in 125 said passageway; a well surrounding the upper end of said nozzle; means for supplying fuel to said well, and an inverted thimble loosely surrounding the upper end of said nozzle, said thimble having one or more air 130

bleed holes therein, and means forming a well surrounding said thimble.

5. In a carburetor, a downwardly conducting passageway; a concentric fuel nozzle in said passageway; a well surrounding the upper end of said nozzle; means for supplying fuel to said well, an inverted thimble loosely surrounding the upper end of said nozzle, and a plurality of ports at different levels in 10 the wall of said thimble.

6. In a carburetor, means forming a mixing conduit, a downwardly directed main venturi in said conduit, a primary venturi mounted above said main venturi, said primary venturi terminating and discharging at a point near the throat of said main venturi, means comprising a nozzle for supplying fuel to said primary venturi at a point near the throat thereof, means forming a 15 source of fuel supply, a well connected to receive fuel from said source of supply and to supply fuel to said nozzle, and an air supply conduit for said well, said air supply conduit having an upwardly directed air receiving opening exposed to the impact of air flowing through said mixing conduit.

7. In a carburetor, means forming a mixing conduit, a downwardly directed main venturi in said conduit, a throttle valve below said venturi, a primary venturi mounted above said main venturi, said primary venturi discharging at a point near the throat of said main venturi, means forming a main fuel discharge outlet arranged to discharge 30 at a point near the throat of said primary venturi, means forming a source of fuel supply, means forming a low speed fuel discharge outlet adjacent said throttle, a well connected to supply fuel to said main fuel discharge outlet, branched conduit means having an inlet to receive fuel from said source of supply and connected to both of said discharge outlets, and an air supply conduit for said well, said air supply conduit 35 having an opening within said mixing conduit.

8. In a carburetor, means forming a substantially vertical mixing conduit, a throttle valve at the lower end of said conduit, a 40 downwardly directed main venturi in said conduit above said throttle valve, means forming a source of fuel supply, a pump connected to receive fuel from said source, said pump having a member connected to and operated by said throttle for discharging a quantity of fuel into said mixing conduit when said throttle is opened, said pump having a discharge nozzle arranged to discharge 45 at an angle to the axis of said mixing conduit, and a substantially vertical member mounted in the line of discharge of said pump nozzle, whereby the stream of fuel from said nozzle may be prevented from striking the outer wall of said mixing conduit.

9. In a carburetor, means forming a sub-

stantially vertical down draft mixing conduit, said conduit having main venturi between the ends thereof and a primary mixing conduit substantially coaxial with said main venturi and discharging at a point near 70 the throat thereof, a main fuel supply device for supplying fuel to said primary mixing conduit, an auxiliary fuel supply device having a nozzle for discharging a stream of fuel, said nozzle being mounted at an angle to the 75 vertical and being directed to discharge against a wall of said primary mixing conduit, whereby under conditions such that the air velocity in said carburetor is so low as to be incapable of instantly breaking up and 80 vaporizing said stream, the unvaporized fuel of said stream may impinge upon a wall of said primary mixing conduit and be drained down to a point near the throat of the main venturi without coming in contact with the 85 wall thereof.

10. In a down draft plain tube carburetor, means forming a mixing conduit having relatively restricted and unrestricted portions, said mixing conduit comprising inner and outer passages, means for admitting air to the upper end of said passages, and a mixture discharge outlet at the lower end, said inner passage having an air bled main nozzle, a throttle valve at the lower end of said mixing 90 conduit, a low speed fuel discharge port adjacent said throttle valve, said low speed port and said main nozzle being interconnected, an auxiliary fuel supply device comprising a nozzle discharging into one branch of said 95 mixing conduit at an angle to the vertical, the stream of fuel from said auxiliary fuel supply device discharging against a wall of said inner passageway when the air velocity is so low as not to substantially deflect it, the 100 lower end of said inner passageway terminating at a point of high restriction in said outer passage.

11. In a down draft carburetor, means forming a substantially vertical mixing conduit, a throttle valve at the lower end of said conduit, said conduit comprising an outer passage and a substantially concentric inner passage, said passages converging at the lower end of the inner passage, a main venturi in said conduit having a throat substantially at the level of the lower end of the inner passage, said inner passage comprising an annular wall terminating at its lower end substantially at the level of the throat of said venturi, a low speed fuel supply nozzle discharging into said mixing conduit at a point adjacent said throttle, a fuel pump having a nozzle mounted at an angle to the vertical and directed towards a wall of said inner passage, said pump being connected to and operated by said throttle and adapted to discharge a stream of fuel toward said wall of said inner conduit when the throttle is opened, whereby when the air velocity in 110 115 120 125 130

said carburetor is too low to instantly break up the fuel stream issuing from the pump, said stream will impinge against and be directed by the wall of said inner passageway 5 to the throat of said main venturi.

12. In a carburetor, means forming a mixing conduit, said mixing conduit having an unrestricted air inlet of constant size regardless of suction and a mixture discharge outlet, a throttle for controlling said discharge outlet, a venturi anterior to said throttle, said venturi having a throat forming the point of high restriction and high suction in said mixing conduit, suction operated means 10 for discharging a mixture of fuel and air to the throat of said venturi during normal and high speed operation, suction operated means for discharging a mixture of fuel and air to said mixing conduit adjacent said 15 throttle for low speed operation, an accelerating pump for discharging additional fuel to said mixing conduit for acceleration only, said pump comprising a piston, a cylinder, inlet and outlet check valves and a discharge 20 nozzle, said discharge nozzle having its outlet at a point of low restriction and low suction in said conduit, whereby the tendency of said pump to continuously discharge fuel during high speed operation of the carburetor will be minimized.

13. In a down draft carburetor, means forming a substantially vertical mixing conduit, said mixing conduit comprising a downwardly directed air inlet, inner and 25 outer passages and a mixing chamber at the lower end of said mixing conduit, a main venturi at the upper end of said mixing chamber, said inner conduit extending to the throat of said main venturi, the walls of 30 said inner conduit and the throat of said venturi forming a restriction in said outer conduit, said inner conduit having a restricted portion therein, a suction operated nozzle discharging at said restricted portion, an 35 accelerating pump and a discharge nozzle for said accelerating pump having its outlet in one of said passages at a point below the level of said air inlet and above the level of the restricted portion in the branch in which 40 it discharges.

In testimony whereof I affix my signature
this 21st day of April, 1930.

GEORGE M. BICKNELL.
